(57) **CLAIM**

We claim the ornamental design for a surveillance camera, as shown and described.

DESCRIPTION

FIG. 1 is a front perspective view of a surveillance camera of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a cross-section view taken along the line **8-8** of FIG. 2.

The broken lines depict portions of the surveillance camera in which the design is embodied that form no part of the claimed design. Additionally, the dot-dash lines denote the boundary of the claim and form no part of the claimed design. The dark gray surface shading in FIGS. 1-6 represents the color black.
